US00D404369S

United States Patent [19]

Kawachi

[11] Patent Number: Des. 404,369

[45] Date of Patent: **Jan. 19, 1999

[54] **MANIFOLD COVER FOR USE IN A SEMICONDUCTOR WAFER HEAT PROCESSING APPARATUS**

5,314,574 5/1994 Takahashi ..... 414/935 X
5,320,218 6/1994 Yamashita et al. ..... 414/935 X
5,752,796 5/1998 Muka ..... 414/935 X

[75] Inventor: **Satoshi Kawachi**, Shiroyama-machi, Japan

Primary Examiner—Brian N. Vinson
Attorney, Agent, or Firm—Ladas & Parry

[73] Assignee: **Tokyo Electron Limited**, Tokyo-to, Japan

[57] CLAIM

[**] Term: **14 Years**

I claim the ornamental design for a manifold cover for use in a semiconductor wafer heat processing apparatus, as shown and described.

[21] Appl. No.: **82,981**

DESCRIPTION

[22] Filed: **Feb. 2, 1998**

FIG. 1 a perspective view of a cover manifold cover for use in a semiconductor wafer heat processing apparatus;

[30] **Foreign Application Priority Data**
Aug. 20, 1997 [JP] Japan 9-65097

FIG. 2 a front elevational view thereof;

[51] **LOC (6) Cl. 13-03**

FIG. 3 a rear elevational view thereof;

[52] **U.S. Cl. D13/182**

FIG. 4 a top plan view thereof;

[58] **Field of Search D13/182; D15/144, D15/144.1, 199; 414/935-941, 217, 147; 437/247, 946**

FIG. 5 a bottom plan view thereof;

[56] References Cited

FIG. 6 a right side view thereof;

FIG. 7 a left side view thereof; and,

FIG. 8 a cross-sectional view taken along line VIII-VIII in FIG. 2.
